FLUORESCENT FIXTURE

Robert Thallon, San Francisco, Calif., assignor, by mesne assignments, to All-Brite Fluorescent Fixtures, Inc., a corporation of California

Application February 21, 1955, Serial No. 489,426

9 Claims. (Cl. 240—9)

This invention relates to improvements in fluorescent light fixtures.

The present invention provides an improved fluorescent light fixture unit which is adapted for use either independently or in association with one or more adjoining units having identical or similar constructions. Each fluorescent light fixture unit embodies novel means which permits the convenient extension of the electrical wires supplying electrical energy to the fluorescent tubes from one fixture unit to another. The light fixture units each support two translucent plastic panels which are arranged in an enclosing position beneath two fluorescent tubes, the said translucent panels being capable of diffusing the light rays so the area beneath is uniformly lighted.

An object of the present invention is to provide an improved fluorescent light fixture embodying a suitable enclosure having a rectangular or other suitably shaped translucent panel supported in a light intercepting position below two fluorescent tubes, the said panel being adapted to diffuse the light emanating from the tubes and thereby uniformly light the area beneath.

Another object of my invention is to provide an improved fluorescent light fixture unit having a novel construction for supporting the electrical wiring so it is held in an out-of-the-way, concealed position where it may be extended from one light fixture unit to another.

Another object of my invention is to provide a novel translucent light diffusing plastic panel having a novel shape and construction which is so designed and constructed as to effect a uniform distribution of light.

Other and further objects of my invention will be pointed out hereinafter, or will be indicated in the appended claims or will be obvious to one skilled in the art upon an understanding of the present disclosure. For the purpose of this application, I have elected to show herein certain forms and details of a fluorescent light fixture which is representative of my invention; it is to be understood, however, that the embodiment of my invention herein shown and described is for the purpose of illustration only and that therefore it is not to be regarded as exhaustive of the variations of the invention in the art.

In the accompanying drawings:

Fig. 1 is a bottom view of a fluorescent light fixture unit embodying my invention, showing parts broken away and in section;

Fig. 2 is a sectional view taken on the line 2—2 of Fig. 1;

Fig. 3 is an enlarged sectional view taken transversely through the unit, showing the hinged member used to support adjacent sides of two translucent panels;

Fig. 4 is an enlarged sectional view taken on the line 4—4 of Fig. 1;

Fig. 5 is an enlarged detail showing the means employed for releasably securing the hinged panel supporting member against downward displacement;

Fig. 6 is a perspective view of two fluorescent light fixture units arranged in side by side relationship, one

2

of the units having two of its translucent panels removed;

Fig. 7 is a perspective view of a wire supporting and concealing member;

Fig. 8 is a perspective view of one of the triangular brackets;

Fig. 9 is an enlarged sectional view taken on the line 9—9 of Fig. 1; and

Fig. 10 is a sectional view taken on the line 10—10 of Fig. 9.

10 In the embodiment of my invention illustrated on the accompanying drawings an enclosure, preferably of rectangular shape, is shown as having a top side 1, opposed ends 2, 2 and opposed sides 3, 3. The ends and sides are each provided with inwardly disposed flanges 2a and 3a, respectively, the said flanges lying in a substantially horizontal plane.

Secured to the top side 1 of the enclosure is an inverted, longitudinal trough-like channel piece 4, which is arranged mid-way between the sides 3, with its opposite ends abutting the ends 2, 2 of the enclosure. The lower side of the trough-like channel piece is partially enclosed at its ends by permanently affixed closure members 5, which in cross-section are substantially inverted V-shaped, the said closure members carrying rigid depending screws 25 which are engaged by nuts to secure a longitudinal enclosing member 6 in an attached position extending across and closing the opening in the lower side of the trough-like channel piece 4. The channel piece 4 normally encloses the electrical wires and transformer used in the electrical system.

30 Hingedly secured at one of its ends to a flange 3a of a side 3 of the enclosure is an adjacent panel supporting bar 7 which is adapted to swing downwardly from a horizontal panel supporting position to an out-of-the-way position where a panel may be inserted into the enclosure during an installation operation or removed when a light tube is to be replaced. The bar 7 is formed with panel supporting portions lying in substantially the same horizontal plane of the flanges 2a and 3a and with a longitudinal upstanding centrally disposed rib 7a

35 which is adapted to prevent the inward shifting of either of two supported panels, as will be later described. That end of the bar opposite its hinged end carries an upstanding globular fastener 8 which is adapted to enter an opening in a deformable resilient socket 9 secured to a side of the enclosure, when the bar is swung upwardly to its panel supporting position. The tension of the socket against the globular fastener 8 normally, but releasably, holds the bar in a horizontal position.

40 Secured against the ends 2, 2 of the enclosure are tube-sockets 10 which support fluorescent light tubes 11 and provide terminals for electrically connecting the tubes to the electrical circuit.

45 Supported on the inwardly protruding flanges 2a and 3a and the bar 7 are two translucent light diffusing panels 12 of substantially the same shape and size which are made preferably from thin vinyl plastic sheets. The panels each have a horizontal bottom surface 12a which is preferably formed throughout its area with embossed protuberances and depressions which increase the rigidity of the panel. The panels each have beveled or outwardly inclined edges 12b connecting the outer edges of the bottom surface 12a with outwardly disposed horizontal and co-planar flanges 12c that engage with and rest upon the flanges 2a and 3a of the enclosure and the bar 7. The flanges 12c are preferably reinforced and made more rigid by a metal edging, although if so desired, the rigidity of the flanges may be increased by other means, such as by increased thickness of the plastic material forming the edge portions of the flanges. The inclined edges 12b of a panel 12 make it possible to insert such panel through the opening in the enclosure when an

installation is being made, and later when positioning the panel in place with the flanges 12c thereof resting on the flanges 2a and 3a of the enclosure, such inclined edges 12b cause the panel to become automatically and quickly guided into its correct enclosing position whereby all but its flanges project through and below the opening in the enclosure. As the panel drops downwardly into its supported position, the inclined sides thereof come into contact with the inwardly protruding flanges 2a and 3a and automatically guide the panel into a position in which its flanges 12c rest firmly on the flanges 2a and 3a.

The enclosure within which the light tubes, the electrical wiring and other parts of the fixture are housed is made preferably of sheet steel or other suitable, rigid material which is not apt to bend or become damaged when handled in the normal manner.

When two or more light units such as the one just described are arranged in side-by-side adjoining relationship as shown on the drawings, means of the type about to be described is used to secure rigidly the adjacent sides 3 of the two units firmly together. The sides 3 of the enclosures are provided with correspondingly positioned holes near their opposite ends which, when the adjacent sides of two units are placed in side-by-side relationship, are in registry with one another. Extending through such registering holes is a tubular bolt 13 having an enlarged head at one end and an exteriorly threaded portion which is adapted to be engaged by a nut 14. The head of the tubular bolt 13 bears against one side of a three-sided fitting 15 and the nut 14 bears against the inside surface of the adjacent side 3 of an adjoining enclosure, and upon the screwing of the nut on the tubular bolt the two adjacent sides of the two enclosures and the fitting are securely clamped together. The opposite ends of the sides of the two enclosures are similarly secured together. The three sided fitting 15 is formed with two rectangular sides 15a and 15b of unequal areas and a lower triangular side 15c which joins the rectangular sides and holds them in positions whereby one of such rectangular sides is disposed at an acute angle with respect to the other. Electrical wires 16 which supply electrical current to the fluorescent tubes extend through the tubular bolt 13 from the interior of one enclosure to the interior of the other. The wires extend through a suitable hole located in a side of the trough-like channel piece 4 near an end of the latter and secured to such side by a similar tubular bolt and nut is a similar three sided fitting 15. The two fittings 15 are disposed with their triangular sides 15c facing downwardly, and the openings between the diverging ends of the rectangular sides 15a and 15b facing toward each other. The wires 16 extend diagonally from one tubular bolt 13 to the other, across a portion of the top side 1 of the enclosure, and into the channel piece 4. So as to conceal the wires from view and support them in a position where they do not interfere with the fluorescent tubes and the installation or replacement thereof, I have provided means for accomplishing these results. Such means embodies an elongated channel member 17 which underlies and substantially engages the top side 1 of the enclosure, the wires 16 being enclosed within the channel of the said member and supported by the horizontal elongated closed side thereof. The elongated horizontal side of the channel member is extended and bent at right angles to form depending end flanges 18 which partially fit inside the openings between the diverging ends of sides 15a and 15b of the fittings 15. The flanges 18 are formed with outwardly protruding ears 19 which extend above and in engaging relation with the upper surfaces of the triangular sides 15c of the fittings 15. The position of the ears 19 of the flanges 18 in overlying engaging positions with respect to the triangular sides of the fittings 15 normally prevents the downward displacement of the

channel member 17. The flanges 18, being resilient, are snapped into place by forcing them upwardly against the free edges of the triangular sides 15c of the fittings 15. The portions of the wires 16 which overlie the channel member are supported thereby and concealed from view.

It is to be noted that adjacent sides 2 of two similar enclosures of two fixture units may be formed with holes for the purpose of connecting such two enclosures together in the manner described, thereby also making it possible for the electrical wires to extend from one enclosure to another. It is also to be understood that the bottom surfaces of the panels 12, which are substantially flat, may be formed with various shapes or designs, or such surfaces may be smooth with no irregularities at all.

What I claim is:

1. In an electrical light fixture, an enclosure having a top side, depending opposed lateral sides and opposed ends, the said enclosure having a bottom opening and the sides and ends having inwardly protruding flanges, a longitudinal wire enclosing channel member mounted against the top side of the enclosure and having longitudinal sides, fluorescent tube supporting sockets arranged to opposite sides of the channel member and adjacent the ends of the enclosure, one side of the channel member and an adjacent lateral side of the enclosure having side openings therein, apertured fittings secured within the side openings of the channel member and the enclosure, the fitting secured within the opening in the side of the enclosure having means securing such side to a side of a similar enclosure, an elongated wire supporting channel element extending between the fittings and having depending end flanges secured to and supported by the fittings, the said channel element having a lower longitudinal bight-providing side and an enclosed elongated channel arranged in communication with the apertures of the fittings, and one or more translucent panels supported on the flanges of the ends and lateral sides of the enclosure, in an enclosing position with respect to the bottom opening of the enclosure.

2. In an electrical light fixture, an enclosure having a top side, depending opposed lateral sides and opposed ends, the said enclosure having a bottom opening, a wire-enclosing housing mounted against the top side of the enclosure and having depending side walls, said housing being spaced laterally of at least one of said enclosure sides, fluorescent tube supporting sockets secured to the enclosure structure adjacent its ends and spaced inwardly of its sides, one side of the housing and the laterally spaced side of the enclosure having side openings therein, apertured fittings secured within the side openings of the housing member and the enclosure, the fittings secured within the opening of the lateral side of the enclosure having means for securing such enclosure side to a side of a similar enclosure, an elongated wire-supporting channel element extending between the fittings, said fittings having channel end-supporting portions, and the channel element providing side walls and an intermediate wire-supporting bight wall defining an elongated channel arranged in communication with the apertures of the fittings.

3. The structure of claim 2, and one of said fitting and channel element members having yielding means engaging the other adjacent the end of the channel member for disposing the channel member against the surface of the top side of said enclosure.

4. The structure of claim 2, and said wire enclosing housing comprising a channel form member extending from adjacent one end of the enclosure to a point adjacent the other end.

5. The structure of claim 2, and said wire enclosing housing comprising a channel form member extending from adjacent one end of the enclosure to a point adjacent the other end, and said fittings disposed at different distances from one end of the enclosure so that the channel element extends diagonally toward the en-

closure side so as to facilitate end engagement of same with said fittings.

6. The structure of claim 2, and said channel element extending diagonally from said housing wall to said side enclosure wall, said fittings having diagonally aligned channel element supporting portions, and the fitting-engaging portion of the channel ends being yieldable to and from an operative fitting engagement position whereby the channel element can be readily attached to and detached from the fittings.

7. In a fluorescent lighting fixtures comprising a first and a second inverted box-like unit, each of said units providing a top wall and depending side and end walls, and the first unit having an electric current supply wire-receiving ballast housing adjacent its top wall and extending between its end walls, said housing having side walls and there being fluorescent tube end-receiving sockets at opposite sides of said wire-receiving housing and disposed below the plane of the housing top, a side wall of said first unit disposed contiguous with a depending wall of said second unit; the combination of wire-supporting and concealing means for branch wires leading from the wire-receiving housing of the first unit for supplying electrical current for a lighting tube of the second unit, the housing side wall and said contiguous unit walls having wire passage-providing openings extending therethrough, fittings incorporated in said wire supporting and concealing means and having wire passage-providing portions secured within said wall openings, the contiguous unit wall-carried fitting having means securing said walls together, a branch wire-supporting and concealing member, fitting-provided supporting means for the latter and projecting away from the related side walls of the housing and first unit respectively, said fitting-provided supporting means removably supporting opposite ends of the wire-supporting member so as to dispose the latter adjacent the top wall of said first unit above the plane of said sockets, and said fitting-provided supporting means and adjacent wire-supporting member end providing a substantially concealed wire accommodating space communicating with the wire passages of the respective fittings.

8. In a fluorescent lighting fixture comprising a first and a second inverted box-like unit, each of said units providing a top wall and depending side and end walls, and the first unit having an electric current supply wire-receiving housing adjacent its top wall, said housing having side walls and there being fluorescent tube end-receiving sockets disposed inwardly of opposite sides of said first unit adjacent each end wall thereof and below the plane of the housing top, a side wall of said first unit disposed contiguous with a depending wall of said second unit; the combination of wire-supporting and concealing means for branch wires leading from the housing of the first unit for supplying electrical current for a lighting tube of the second unit, the housing side wall and said contiguous unit walls having wire passage-providing openings extending therethrough, fittings in-

corporated in said wire-supporting and concealing means and having wire passage-providing portions secured within said wall openings, the contiguous unit wall-carried fitting having means securing said walls together, a branch wire-supporting and concealing member, fitting-provided supporting means for the latter, and projecting away from the related side walls of the housing and first unit respectively, said fitting-provided supporting means removably supporting opposite ends of the wire supporting member so as to dispose the latter adjacent the top wall of said first unit above the plane of said sockets, and the ends of the wire supporting member communicating with the wire passage of the related fitting.

9. In a fluorescent lighting fixture comprising a first and a second inverted box-like unit, each of said units providing a top wall and depending side and end walls, and the first unit having an electric current supply wire-receiving housing adjacent its top wall, said housing having side walls and there being fluorescent tube end-receiving sockets disposed inwardly of opposite sides of said first unit adjacent each end wall thereof, a side wall of said first unit disposed contiguous with a depending wall of said second unit; the combination of wire-supporting and concealing means for branch wires leading from the housing of the first unit for supplying electrical current for a lighting tube of the second unit, the housing side wall and said contiguous unit walls having wire passage-providing openings extending therethrough, fittings incorporated in said wire-supporting and concealing means and having wire passage-providing portions secured within said wall openings, the contiguous unit wall-carried fitting having means supporting the adjacent second unit wall, a branch wire-supporting and concealing member, fitting-provided supporting means for the latter, and projecting away from the related side walls of the housing and first unit respectively, said fitting-provided supporting means removably supporting opposite ends of the wire supporting member so as to dispose the latter adjacent the top wall of said first unit above the plane of said sockets, and the ends of the wire supporting member communicating with the wire passage of the related fitting.
